UNITED STATES PATENT OFFICE.

ALFRED R. L. DOHME, OF BALTIMORE, MARYLAND, ASSIGNOR TO SHARP & DOHME, INC., OF BALTIMORE, MARYLAND, A CORPORATION OF NEW JERSEY.

PRODUCTION OF ALKYL RESORCINOLS.

No Drawing. Application filed April 16, 1925, Serial No. 23,701. Renewed October 31, 1928.

This invention relates to an improved method of making alkyl resorcinols, including not only the lower alkyl resorcinols such as propyl and butyl resorcinols, but also the 5 higher alkyl resorcinols, such as amyl, hexyl, heptyl, octyl, dodecyl resorcinols, etc.

The present invention relates particularly to the production of alkyl resorcinols from acyl resorcinols which may be obtained in 10 high yields by condensation of resorcinol and fatty acid with zinc chloride for example, by gradually adding resorcinol to a heated mixture of zinc chloride and fatty acid with agitation of the mixture and with maintenance 15 of the temperature of the reaction mixture at about 125-145° C. and with the use of a small amount of zinc chloride which may be only a small fraction of the weight of the fatty acid, e. g., around one-fifth the weight 20 of the acid. The acyl resorcinol can be obtained in this way with the avoidance of any large amounts of tarry by-products and in a form such that it can be further treated with a minimum of purification for the production 25 of the alkyl resorcinol. The acyl resorcinol can be purified, if necessary or desirable, before using it. It is not necessary to obtain a product of the highest purity 30 but the acyl resorcinol produced in the form of an oil can advantageously be used for the production of alkyl resorcinol in accordance with the present invention. Where this oil is not of sufficient purity it can be further purified, e. g., by redistillation, crystallization 35 from solvents, etc. Instead of using acyl resorcinols produced in this way, acyl resorcinols otherwise produced and of suitable purity may be used in accordance with the improved process of the invention for the making of alkyl resorcinols therefrom. 40 That is, the improved process of the invention may make use of acyl resorcinols produced in any suitable way; but it may ad-

vantageously make use of the acyl resorcinols produced in the form of an oil in accordance 45 with the process hereinbefore described.

In the production of certain of the lower alkyl resorcinols from the corresponding acyl resorcinols, it has been proposed to effect the reduction by the use of zinc amalgam in 50 large amount and in the presence of hydrochloric acid. It has thus been proposed to use an amount of zinc amalgam equal to about eight times the weight of the acyl resorcinol, together with about 5 parts of hydrochloric 55 acid and 5 parts of water. This reaction is not only slow, requiring about twenty-nine hours at the boiling point of the reduction mixture, but further amounts of hydrochloric acid must be added during the progress of the 60 reaction.

According to the present invention, a radically reduced amount of zinc amalgam is used, and the reduction is effected in a greatly reduced period of time. In the present process the amount of zinc amalgam is reduced to about two and one-half times the weight of the acyl resorcinol, and the reduction is carried out with vigorous agitation of the reduction mixture. 65

In carrying out the present process, for example, one part by weight of the acyl resorcinol is reduced by about two and one-half parts by weight of zinc amalgam, using about five parts of hydrochloric acid (20° 70 Bé.) and about six parts of water, and the reduction mixture being vigorously agitated and maintained at a temperature of about 105° C. By proceeding in this way the reduction is finished in about ten to twelve 75 hours. The reduction product may then be washed with an equal volume of water and then distilled in vacuo, whereby the water is 80 first distilled off and finally the alkyl resorcinol. 85

The zinc amalgam is made by amalgamat-

ing mossy zinc with a 2% solution of mercuric chloride. The completion of the reduction may be readily determined by testing a few drops of the oily product dissolved in a few cc. of alcohol with a drop of ferric chloride solution. When the reduction is completed, no red coloration will be shown by this test.

The improved reduction process of the present invention is not only effected in a greatly shortened period of time, but gives better yields and a higher purity of product. The reduction is, moreover, effected with vigorous agitation of the reduction mixture, thus bringing about the formation of a semi-emulsion in which the oil is intimately admixed with and distributed through the aqueous acid.

The invention will be further illustrated by the following specific example describing the production of hexyl resorcinol.

While the pure crystalline hexyl resorcinol can be used for the production therefrom of hexyl resorcinol, it is not necessary to use the hexyl resorcinol in a pure state.

The method of reduction will be illustrated by the following example:

One part by weight of hexyl resorcinol is reduced by $2\frac{1}{2}$ parts of zinc amalgam in five parts of hydrochloric acid (20 Bé.) and six parts of water, with vigorous stirring at about 105° . The reduction is complete in ten to twelve hours. The reduction product is washed with an equal volume of water and the water layer separated. The reduction product is then distilled in vacuo whereby the last traces of water are removed and finally the hexyl resorcinol is distilled. It has a boiling point of 215 to 220° at 18 mm. On cooling, the distillate solidifies and the solid possesses a melting point of 45 to 55° . The solidified distillate from the second distillation (boiling point 170 to 180° at 8 mm.) possesses a melting point of 49 to 56° . When this second distillate is crystallized from a mixture of toluene and petroleum ether white crystals are obtained of a melting point of 57 to 58.5° . This product is of high purity. It can be further purified to give a product of somewhat higher melting point.

In a similar way other alkyl resorcinols can be produced from the intermediate ketones. Among the alkyl resorcinols which can be thus obtained may be mentioned the following, the melting point and boiling point in

degrees centigrade of each compound in a purified state being given:

	Melting point	Boiling point— 6-7 mm.	60
Propyl resorcinol	80-81.5	158-159	
Butyl resorcinol	47-48	164-166	
Amyl resorcinol	71.5-73	168-170	
Hexyl resorcinol		178-179	65
Heptyl resorcinol	73-74.5	188-188	
Octyl resorcinol	74-75	190-201	
Dodecyl resorcinol	80-81.5	224-226	
Iso-butyl resorcinol	62-63.5	166-168	
Iso-amyl resorcinol	61-62.5	177-178	
Iso-hexyl resorcinol	70-71.5	182-183	

It will thus be seen that the present invention provides an improved process of making alkyl resorcinols in high yield from acyl resorcinols with the use of radically reduced amount of zinc amalgam and with vigorous agitation of the reduction mixture whereby the reduction is completed in a greatly shortened period of time.

The improved process is applicable not only to the production of the lower alkyl resorcinols, certain of which have been heretofore known and produced, but also and particularly to the production of the new higher alkyl resorcinols.

I claim:

1. The method of making alkyl resorcinols which comprises subjecting acyl resorcinols to reduction with zinc amalgam and hydrochloric acid, the amount of zinc amalgam not exceeding about two and one-half times the weight of the acyl resorcinol, and the reduction being effected with vigorous agitation of the mixture at a reactive temperature.

2. The method of making hexyl resorcinol which comprises subjecting hexyl resorcinol to reduction with zinc amalgam and hydrochloric acid, the amount of zinc amalgam not exceeding about two and one-half times the weight of the hexyl resorcinol, and the reduction being effected with vigorous agitation of the mixture at a reactive temperature.

3. The method of making hexyl resorcinol which comprises subjecting hexyl resorcinol to reduction with zinc amalgam and hydrochloric acid, the amount of zinc amalgam not exceeding about two and one-half times the weight of the hexyl resorcinol, and the reduction being effected with vigorous agitation of the mixture at a temperature of about 105° C.

In testimony whereof I affix my signature.

ALFRED R. L. DOHME.
